CLOCK

Burton Kelly, Bellwood, Ill., assignor to Sunbeam Corporation, Chicago, Ill., a corporation of Illinois

Filed July 10, 1962, Ser. No. 70,869

Term of patent 14 years

(Cl. D42—7)

FIG. 1 is a front perspective view of a clock embodying my new design;

FIG. 2 is a side elevational view thereof;

FIG. 3 is a top plan view thereof;

FIG. 4 is a rear elevational view thereof; and

FIG. 5 is a sectional side elevational view taken along line 5-5 of FIG. 1.

The characteristic feature of my design resides in the combination on the rectangularly framed clock shown of a plurality of inner rectangular, framed areas of which several are panelled and several are open, one inner rectangle enclosing the clock face per se which includes radiating hour marks provided with enlargements at their

outer ends and substantially rectangular, tapered hands, all as shown.

I claim:

The ornamental design for a clock, as shown and described.
